MACHINE FOR COILING METAL STOCK

John Balla, Sr., Schenectady, N. Y.

Application July 6, 1944, Serial No. 543,694

15 Claims. (Cl. 153—64)

1

This invention pertains to a machine for coiling metal stock, and more particularly and specifically to a machine for manufacturing coil springs and spring lock washers.

The primary object of the invention is the provision of such a machine in which the forming of the spring or lock washer and the severance of the stock on the completion of the formation of the spring or washer is continuous and uninterrupted enabling the machine to have great capacity with a resultant decrease in cost of production.

A further object of the invention is the provision of such a machine wherein the adjustments or changes incident to enabling the machine to make springs or lock washers as desired is extremely simple and rapid of accomplishment.

Another object of the invention is that of providing a machine which by easily and rapidly obtainable reversal of the parts enables the machine to make either right or left coiled springs or lock washers.

A still further object is the provision of a machine which is capable of producing springs or lock washers of varying diameters and to work metal stock of different cross sectional dimensions.

Other objects, novel features of construction and improved results of the machine will appear from the following description when read in the light of the accompanying drawings.

In the drawings:

Fig. 1 is a side elevation of a machine embodying the invention.

Fig. 2 is an end view of the front or product delivery end of the machine.

Fig. 3 is a vertical sectional view on the line 3—3 of Fig. 1 looking in the direction indicated by arrows.

Fig. 4 is a vertical sectional view on the line 4—4 of Fig. 1 looking in the direction indicated by arrows.

Fig. 5 is a longitudinal vertical sectional view.

Fig. 6 is a vertical sectional view on the line 6—6 of Fig. 2 looking in the direction indicated by arrows.

Fig. 7 is a vertical sectional view on the line 7—7 of Fig. 2 looking in the direction indicated by arrows.

Fig. 8 is a vertical sectional view on the line 8—8 of Fig. 2 looking in the direction indicated by arrows.

Fig. 9 is a vertical sectional view on the line 9—9 of Fig. 2 looking in the direction indicated by arrows.

2

Fig. 10 is a vertical sectional view on the line 10—10 of Fig. 2 looking in the direction indicated by arrows.

Fig. 11 is a detail perspective view of an element of the clamp D.

Fig. 12 is a front view of the metal stock guide.

Fig. 13 is a front view of the stock guide with the front plate thereof removed.

Fig. 14 is a detail vertical sectional view through the cam throw adjustor.

Fig. 15 is a horizontal sectional view on the line 15—15 of Fig. 14 looking in the direction indicated by arrows.

Fig. 16 is a fragmentary detail vertical sectional view on the line 16—16 of Fig. 1 looking in the direction indicated by arrows.

Fig. 17 is a horizontal section taken on the line 17—17 of Fig. 16 looking in the direction indicated by arrows.

Fig. 18 is a vertical sectional view on the line 18—18 of Fig. 5 looking in the direction indicated by arrows.

Fig. 19 is a detail view similar to Fig. 2 illustrating the use of a plurality of cutter blades as utilized in the manufacture of lock washers.

Fig. 20 is a sectional view on the line 20—20 of Fig. 19 looking in the direction indicated by arrows.

Fig. 21 is a detail fragmentary vertical sectional view illustrating the formation of a lock washer.

Fig. 22 is a fragmentary detail view partly in vertical section illustrating a modified form of construction suitable for the manufacture of coil springs.

Fig. 23 is a vertical sectional view similar to Fig. 8 illustrating the construction of stock guide for stock used in the manufacture of lock washers.

Fig. 24 is a front view of a lock washer as produced by the machine.

Fig. 25 is an edge view of the same lock washer.

Fig. 26 is a side view of a coil spring as produced by the machine.

Fig. 27 is a top plan view of the machine appearing in Fig. 1 of the drawings.

Fig. 28 is a side view of the standard adjacent the front end of the machine.

Fig. 29 is a side view of the standard at the rear end of the machine.

Fig. 30 is a side view of the standard intermediate the ends of the machine.

Fig. 31 is a side view of a bearing block for the countershaft.

55 Referring now to the drawings and using like

letters and reference numerals to designate similar parts throughout the description, 1 is a suitable base, upon the upper face of which are vertical standards 2, 3 and 4 at the front and rear and intermediate the length of the machine respectively. The specific construction of these standards appears in Figs. 28, 29 and 30 of the drawings.

The main drive shaft 5 is suitably rotatably supported in the standards 3 and 4 and suitably connected to any chosen form of power means, not shown, which should be of the type to rotate the shaft 5 in either direction as the direction of rotation for the drive shaft is reversed as the machine is changed from the production of left hand coils to right hand coils, as will hereinafter more fully appear.

A feed roller shaft 6 is rotatably supported in the front and rear standards 2 and 3 respectively and beyond the front face of the standard 2 is provided with a stock feed roller 7 having in its face a marginally disposed, peripheral, annular groove 8 of the proper dimensions and transverse configuration to engage the circular stock 11 of which the coil spring A is to be formed. More detailed description of this construction will hereinafter appear.

A mandrel carrying rotating shaft 10 is rotatably supported in the standards 2 and 4. The shaft is supported to permit limited vertical movement which is accommodated by making the opening 11 in the standard 2 of slightly greater diameter than that of the shaft and by providing a universal type bearing 12 in the standard 4.

The bearing 12 permits of a limited universal movement of the shaft 10. For a considerable portion of its length the shaft is hollow as indicated at 13 and telescopically receives the shaft portion 14 of the mandrel 15. The mandrel is positioned below the stock feed roller 7.

To permit insertion and removal of the mandrel and the substitution of mandrels of different sizes the innermost end of the mandrel shaft 14 is cut away and flattened as at 16. The mandrel shaft is held against rotation and against longitudinal movement within the shaft 10 by a clamp, the specific construction of which appears in Figs. 5 and 18 of the drawings, from which it will be seen that there is a flat plate 17 which is forced in tight clamped engagement with the flat surface 16 by a plurality of set screws 18. This clamp is made as a unit by providing a spring band 19, the set screws being threaded in the thickened portion 20 of the shaft 10.

A shaft 21 is disposed at a slight angle to the horizontal and is suitably rotatably supported in the standards 2 and 4 and carries on its outer face a forming roll 22 and a stock cutter designated as an entirety at B, the specific construction of which will be hereinafter given. The support for the outer end of the shaft 21 is in the form of a block carried bearing 23, which block is suitably secured in the inclined seat 24 of the standard 2. This block at its lower end is provided with a plurality of shims 25 insertable and removable between the lower end of the block and the bottom wall or shoulder 26 of the block seat 24 for a purpose which will hereinafter appear.

An idler roll 27 is carried in a block bearing 28 which is of substantially the same construction as the block 23. This block is suitably secured in the seat 29 of the standard 2 and at its lower end is provided with shims 30 which are insertable and removable between the lower end of the

block and the bottom or vertical shoulder 30' of the seat, the shims being for a purpose which will hereinafter appear.

The standard 2 is provided with the aforementioned opening 11 for the passage of the shaft 10 and with openings 31 and 32 (see Figure 28). The opening 31 is for the passage of the shaft 21 while the opening 32 is for the passage of the shaft 33 which carries the aforementioned idler roll 27. The inner end of the shaft 33 is rotatably supported in the bearing 34. The bearing support for the shaft 33 is such that this shaft is longitudinally reciprocable.

The main drive shaft 5 is provided with gears 35 and 36. A counter shaft 37 is rotatably supported on the standards 3 and 4. At its inner end it carries a gear 38 meshing with an intermediate gear 39 on stub shaft 49 and provides driving connection with the gear 36 for transmitting rotary motion to the shaft 37. The shaft 37 is provided with a second gear 40 meshing with a gear 41 carried by the stock feeding roller shaft 6. This provides rotary drive for the feed roller 7. A third gear 42 on the counter shaft 37 meshes with a gear 43 carried by the shaft 21 and provides rotary motion to said shaft.

A cam C carried by a shaft 44 rotatably mounted in bearing carrying standards 45 and 46 is provided for the purpose of imparting reciprocation to the shaft 33 in a manner which will later appear. The cam shaft 44 carries a gear 47 meshing with a gear 48 on stub shaft 49 provided with a second gear 50 which meshes with the gear 51 carried adjacent the inner end of the shaft 10. This construction imparts rotation to the cam C and shaft 10.

The connection between the cam C and the idler roll shaft 33 will now be described. A standard 52 is secured by bolts 53 to the base 1 (see Figures 3, 14, 15 and 27). A swing arm 54 is pivotally secured to the upper end of the standard and has an end 55 positioned above a camway 56 in the cam. The end 55 of the arm is cut away as at 57 and in its bottom is provided with a longitudinal slot 58 for the passage of the upper end of a stub shaft 59 carrying a roller 60 disposed in the camway 56. A nut 61 is disposed within the cut out portion 57 of the arm and provides means for adjustably securing the stub shaft 59 in adjusted position in the slotted portion 58 of the arm. The arm end 55 is provided with a fitting 62 in its side cooperating with the ball end 63 of a threaded bolt 64 thus providing an universal connection. A similar threaded bolt 65 is provided and the adjacent threaded ends of the bolts 64 and 65 carry a turn-buckle 66. The bolt 65 has universal connection as at 67 with the end 68 of an arm 69 the opposite end 70 of which has operative connection with the shaft 33 for reciprocating said shaft when the mechanism is actuated by the cam. The mechanism just described provides all the adjustments necessary to impart varying degrees of longitudinal movement to the shaft 33 in response to the movement of the cam roller 60 in the camway 56.

The feed roller 7 must be caused to force the metal stock or wire 11 against the mandrel with sufficient force to pull the stock through the machine. This means that the feed roller must be vertically movable and adjustable. The standard 2 upon its top is provided with spaced vertically extending webs 72 and 73 which form a window 14 having vertical guideways 75 (see Figure 28) in which is slidably mounted a bearing block 76 for the front end of the feed roller shaft

6. A coil spring 71 tends normally to hold this block in an elevated position (see Figure 5). The upper end of the window 74 is closed by a cross head 78 in which is mounted a threaded sleeve 79 provided at the top and bottom sides of the cross head with nuts 80 and 81. A cam shaft 82 provided with an actuating handle 83 is rotatable within the sleeve and at its lower end below the nut 81 is provided with a cam 84 (see Figure 2). A cam 85 is opposed to the cam 84 being suitably secured to the upper face or edge of the bearing block 76. Once the proper setting of the feed roller 7 is determined the nut 81 is properly positioned so that when the cam shaft 82 and its cam 84 are rotated into the position illustrated in Fig. 2 of the drawings the metal stock or wire 71 is engaged between the feed roller and the mandrel under the proper force necessary to progress the stock through the machine.

By reason of the shaft 6 having the vertical movement described the rear end of the shaft is rotatably supported in the standard 3 by a bearing 86 which permits of a limited universal movement.

So that the feed roller 7 may at all times be properly positioned in respect to the mandrel 15 irrespective of the diameter or cross sectional configuration of the stock being operated upon provision is made for longitudinal axial movement and adjustment of the shaft 6. It is to be understood that when circular stock, such as that used for springs, of a greater diameter is used, another roller 7 having the proper sized groove 8 will be substituted, likewise this applies to the forming roller 22. When stock of rectangular shape in cross section is being worked a plain or flat faced feed roller is substituted, as will appear from the later description of the manufacture of lock washers. To provide for longitudinal movement of the shaft 6 a threaded stud 87 extends rearwardly from the bearing block 76 and is provided with a yoke block 88. This block is freely slidable on the stud 87 and is held in adjusted position by nuts 89 and 90. The yoke portion 91 of the yoke block 88 engages a collar 92 provided on the shaft 6. Loosening of the nut 90 and tightening of the nut 89 will move the shaft 6 and the feed roller 7 to the right as these parts are viewed in Fig. 5 of the drawings. Movement of the shaft and feed roller in the opposite direction is attained by rotating the nuts 89 and 90 in the opposite direction.

The shaft 6, of course, has its end portion mounted for longitudinal movement as well as for rotation in the bearing 86. So, too, as shown, the gear 41 is made somewhat wider than the gear 40 with which it is in mesh so as to have ample width of tooth engagement between the two gears 40 and 41 at all times.

To put the machine in operation the leading end of the stock must be bent into a semi-circular form and a mechanism for accomplishing this is provided as a part of the machine. This mechanism appears in Figs. 2 and 19 of the drawings and is specifically illustrated in Figs. 9 and 10 of the drawings. D designates a clamp to prevent longitudinal axial movement of the stock 71 after the leading end 93 of the stock has been fed between the rollers 94 and 95 of the stock bender E. The bender comprises a yoke 96 the arms of which are provided with slots 97 (see Figure 10) in which are disposed a pair of tubes 98 and 99 within one of which is threadedly secured a shaft 100 carrying intermediate its ends the aforementioned roller 95 and the shaft having a head at

its outer end to retain the assembly of the roller, shaft and tube members together. This yoke is pivotally supported to a suitable standard 101 (which may be either the front standard 2 of the machine or a separate and specially provided standard, as desired) by a pivot bolt 102 and is provided with a handle 103. The aforementioned roller 94 is carried by the bolt 102 and is disposed in the space between the standard 101 and the yoke. The slots 97 permit vertical movement of the roller 95. Set screws 104 limit the upward movement of the roller 95 and provide means affording adjustment of this roller for operation upon stock of varying dimensions.

Having reference to Fig. 2 of the drawings it will be understood that after the stock 71 is positioned as illustrated movement of the depending handle 103 to the left will swing the roller carrying the roller 95 in a circular path will bend the lead end 93 of the stock into the semi-circular shape illustrated in dotted lines and designated at 93a. It is, of course, understood that, during this stock bending operation, the aforesaid clamp D is tightened to hold the stock from endwise movement.

Specifically, the clamp D comprises a block having therein a vertical extending passageway 175, the opposite faces of which are curved. A wire gripper 177 is positioned in said block passageway and is normally urged into the position, illustrated in Figures 2 and 19, by a coil spring 178. When the gripper is in this position, a jawed opening 179 therein grips the wire and holds it against longitudinal movement. Movement of the gripper 177 to a vertical position by pressure upon its upper end will permit insertion and removal of the wire.

A guide designated as an entirety by F is provided for assuring proper alignment of the stock with the feed roll 7. Having reference specifically to Figs. 6 to 8 inclusive and 12 and 13, it will be seen that there is a pair of opposed plates 105 and 106 which are of a U shape in cross sectional configuration to form a rectangularly tubular housing within which is disposed a pair of guide blocks 107, 108 which have cut-out longitudinally grooved portions in their abutting faces, as at 107a, and registering with each other to provide an opening of the proper configuration and dimensions to snugly receive the stock 71. The block 108 is secured in position by screws 109. The rear or innermost plate 105 adjacent its ends is provided with rounded protuberances 110 which are disposed within suitable rounded bottom depressions 111 and 112 provided in a carrier plate 113 (see Figure 13). The plate 113 adjacent the stock receiving end of the guide is secured to the standard 2 by a bolt 114 about which the plate may be swung to raise or lower its delivery end. This is for the purpose of assuring correct alignment of the stock with the feed roll and mandrel. This plate is held in its adjusted position by a second bolt 115 which passes through the vertically extending slot 116 of the plate. The plate is provided with oppositely positioned ears 117 provided with threaded openings 118 for the reception of bolts 119 which pass through ears 120 provided on the aforementioned rear guide block carrying plate 105. By tightening down and loosening the bolts 119 the guide blocks can be adjusted by a partial lateral swinging or substantially a partial rotation thereof to properly align the stock in the event the stock is twisted as is often the case as the stock does not always come from the source of supply perfectly straight.

The outer plate 106 (see Figures 8, 12, and 23) on its bottom at points adjacent its ends is provided with downwardly projecting tongues 121 which extend through apertures horizontally extending lips 122 carried by the bottom of the inner plate 105. This construction forms a support for the outer plate 106, which plate is further held in the position illustrated in Figs. 6 and 8 by a pivotally mounted latch handle 123 which is normally held behind a latch finger 124 by the action of a coil spring 125 (see Figures 2, 19 and 27). This latch finger is mounted upon and extends forwardly of the top of the rear plate 105. With the latch handle 123 in locked position the parts are in the position illustrated in full line in Figs. 6 and 7. Upon swinging the latch handle 123 about its pivot 126 to disengage it from its holding finger 124 the outer plate can be swung down as illustrated in dotted line in Fig. 6 of the drawings. This makes it possible to insert the stock 71 and also to insert substitute guide blocks when stock of different dimensions or cross sectional configuration is to be worked.

At this point attention is directed to Fig. 23 of the drawings which illustrates guide blocks such as are used when the machine is operated to manufacture lock washers. In this instance the stock 127 is substantially rectangular in cross sectional configuration and guide blocks 128 and 129 have been substituted for the guide blocks 107 and 108 which were used for the circular stock 71 out of which the coil springs are manufactured.

Description will now be given of the cutter B. This apparatus, see particularly Fig. 20 of the drawings, is closely associated with the forming roll 22 and like said roll is carried on the shaft 24. The device comprises a circular plate 130 which has an inner face 131 in opposed relationship to the outer face 132 of the roll 22. The said outer face of the roll 22 at a plurality of points throughout its perimeter is provided with slots 133 within which are reciprocally mounted cutter fingers 134 with cutting blades 135 which are at the outermost ends of the fingers. The inner face 131 of the plate 130 is provided with a spiral groove 136, see Figs. 19 and 20, for the reception of lugs 137 carried adjacent the inboard ends 138 of the cutter fingers. It will be obvious that rotation of the plate 130 will cause the cutting fingers 134 to be projected or retracted in accordance with the direction of rotation of the plate. The cutting edges 135 of the fingers cut through the stock 71 while the same is on the mandrel as clearly appears in Figs. 2 and 19 of the drawings. The fingers are of a length and adjusted so as to extend sufficiently far to completely sever the stock. Once the cutters are properly adjusted the plate 130 is tightened down by the nut 139 which not only holds the plate against rotation independently of the shaft 21 but simultaneously tightly clamps the fingers 134 against the front or outer face 132 of the roll 22.

When the machine is being used in the manufacture of coil springs only a single cutting finger (see Figure 2) is mounted in the cutter while five cutting fingers are mounted in the cutter when the machine is utilized to manufacture lock washers (see Figure 19), as will more clearly appear in the following description of the mode of operation of the machine.

It has been mentioned that the idler roll 27 is movable longitudinally of the machine which movement is effected by the cam C. This roll 27 has its outer peripheral edge beveled as at 140

(see Figures 1, 2 and 19) and as the stock is fed to the mandrel and forced or formed thereagainst by the roller 22 the stock hits this beveled edge 140 and the position of the idler roll 27 will determine the pitch given to the spring convolutions, as clearly appears in Fig. 1 of the drawings. From the description thus far given the operation of the machine in the formation of coil springs will be understandable and said description will describe structural features heretofore not mentioned. The construction of the coil spring A made by the machine appears in Fig. 26 of the drawings wherein it will be seen that there are a plurality of spring convolutions which are spiral in nature, that is the spring is given a pitch so that these convolutions are what are commonly termed open convolutes. At each end however the spring coils or convolutes are nested as indicated at 141. That is, two convolutes are in abutment with one another. The spring is made from circular stock.

The leading end 93 of the stock is bent in the stock bender E in the manner illustrated in the lower left hand corner of Figs. 2 and 19 of the drawings. The latch handle 123 is then operated and the parts of the guide swung into the position illustrated in dotted lines in Fig. 6 of the drawings. The stock is then inserted into the opposed grooves formed in the opposing faces of the guide blocks 107 and 108 while the curved leading end 93a of the stock is placed about the mandrel. Before the stock is placed about the mandrel the mandrel is in a lowered position, being at this time supported by the bearing opening 11 in the front standard 2. The mandrel has dropped down to this supporting position and is not in contact with the feed roller 7. It is to accommodate this dropping movement of the mandrel that the mandrel drive shaft 10 is provided with the universal bearing 12 and the opening 11 in the standard 2 is made larger than the shaft.

With the curved end of the stock in position over the mandrel the mandrel is lifted into the position illustrated in Fig. 2 of the drawings with the stock being engaged by the groove 8 of the feed roller 7 and by the face of the roller 22. It is to be understood that when the stock is being put into the machine the cam 84 is operated by its handle 83 to the reverse position illustrated in Fig. 2 of the drawings. When the stock is in place about the mandrel the cam is operated to the position illustrated in Fig. 2 of the drawings which causes the stock to be tightly clamped against the mandrel and will cause the stock to be continuously pulled into the machine when power is applied to the power shaft 5, with the mandrel 15 and forming roller 22 aiding in feeding of the stock into the machine and onto the mandrel thereof.

During the starting operation of the machine it has been found desirable to provide means for rotating the parts manually and to this end there is provided a shaft 142 (see Figures 1, 3, 4 and 5) provided with a hand wheel or similar means, not shown, by which it may be manually rotated. This shaft is provided with a gear 143 meshing with the main drive shaft carried gear 35.

Upon the power being delivered to the main drive shaft 5 the feed roller 7, or upon operation of said hand operated shaft 142, the mandrel 15, and the form roller 22 with its associated cutter mechanism are simultaneously rotated. This results in the stock being fed to the mandrel and being forced thereagainst and formed thereabout by the form roller 22. The pitch of the

spring convolutes is in accord with the setting of the idler roll 27.

At the same time the aforementioned parts are being rotated so likewise is the cam C being rotated by the main power means. The drive ratio for the cam and the high spots 144 of the cam are such that the idler roll 27 remains in a set position with the roller 60 riding for a considerable time in the major straight concentric portion of the camway 56 to give the desired number of convolutions prior to causing the nesting operation. When however the cam has revolved to a point so that the cam roller 60 rides up on the high spots 144 of the cam the idler roll is retracted through movement of the arm 54 by reason of its connection with the yoke arm 69, as has been explained. This retraction of the idler roll 27 causes nesting of the spring end portions for the reasons explained and the mechanism has been timed and adjusted so that the cutter finger 134 engages the stock in the manner illustrated in Figs. 2 and 19 and severs the stock.

The speed of rotation of the cam C plus the length of the high spots of the cam are such that after severance of the stock occurs nesting is continued to give a leading nested end to the stock in the spring. Immediately thereafter the cam causes the idler roll 27 to move outwardly to its original position. Thus one cycle of the machine has been completed and thereafter the cycle is repeated indefinitely as long as the machine is maintained in operation and stock is being fed therethrough.

Each spring formed by the machine will be of the construction shown in Fig. 26 of the drawings and will have nested convolutes at each of its ends.

The machine has the decided advantage that the feed of stock will be automatically stopped should the stock break as it is being bent or formed about the mandrel. Should the stock break there would be nothing to cause the leading end of the incoming stock to follow the circular contour of the mandrel. The stock on the mandrel in front of the break will be discharged very quickly from the mandrel and thereupon the mandrel will drop down moving away from the stock above it which lies under the feed roll 7. Immediately this happens the feed roll 7 loses its ability to pull additional stock into the machine. When this occurs it is necessary to restart the machine by re-threading the stock in the manner heretofore described wherein it has been pointed out that the leading end of the stock must first be bent into the form illustrated at 93^a in Figs. 2 and 19 of the drawings.

The operation in the manufacture of lock washers is identical to that described in respect to the manufacture of coil springs, with the following exceptions.

The lock washers made by the machine are of the construction illustrated in Figs. 24 and 25 of the drawings from which it will be seen that the stock 127 of which they are composed is substantially rectangular in cross sectional configuration, as has been before pointed out in the specific description of the stock guide appearing in Fig. 23 of the drawings.

By reference to Fig. 21 of the drawings it will be seen that the feed roller 7 has been replaced by a suitable feed roller 145 which has a plain or flat surface so as to properly engage the flat top 146 of the rectangular stock 127.

Having reference now to Fig. 19 which illus-

trates the machine in operation for lock washer manufacture, it will be seen that the cutter assembly B carries five cutting fingers 134. The result of this arrangement is that the stock will be severed each time it has been completely coiled once about the mandrel 15. In other words, only one convolution of the stock is made prior to the severance thereof.

There is no need for the nesting operation as was the case with coil springs. Consequently drive connection between the cam C and the idler roll 27 is broken so that the roll 27 remains in a fixed position so as to give each convolution of the stock the same pitch.

A modified form of the machine as it is utilized for manufacturing springs is illustrated in Fig. 22 of the drawings. The entire modification resides in the idler roll construction. In this instance the idler roll appears at 147 and it is not longitudinally movable. The roll is adjustable to any desired fixed position within reasonable limits by reason of the adjusting nut 148 which abuts the inner end of the roll shaft 149. The roll shaft is provided with a bore within which is slidably mounted a shaft 150 carrying on its outer end a disc 151 which engages the stock 71 and determines the pitch of the spring convolutions. This shaft at its inner end is provided with a collar 152 to which is connected the yoke end 70 of the arm 69 which is an element in the connection to the cam C.

It will be obvious that this construction operates to accomplish the same result as that described in respect to the preferred form of the invention in that the cam will move the disc 151 in and out by sliding the shaft 150 of the disc within the bore of the idler roller shaft. The idler roller 147 will serve to support the mandrel just as does the idler roll 27 of the preferred form of the invention.

Obviously the machine is not limited to the manufacture of springs or washers of any single diameter dimension. When it is desired to change the diameter of the product the mandrel is changed and description has already been given of the manner in which the mandrels are secured in and removable from the mandrel driving shaft 10. As the dimension of the product is increased or decreased a change in the diameter of the feed roll and the forming roll 22 will be required, as will be well understood by mechanics and others skilled in this art.

The machine illustrated and described is for the production of what I have termed left hand springs and washers but were it desired to make right hand products a certain reversal of parts would be necessary and provision has been made for this, as will now be described.

As has been mentioned, the power means is given a reverse direction of rotation when the machine is to make right hand products. The countershaft 37 and its gears are shifted to the opposite side of the machine. To permit this the intermediate standard 4 is provided with bearing block seats similar to those described in respect to the front standard 2 which is specifically illustrated in Fig. 28 of the drawings. Having reference now to Fig. 30 it will be seen that the standard 4 has oppositely arranged bearing block seats 160 and 161 which are adapted to receive the bearing carrying block 162 in the bearing of which is rotatably supported the inboard end of the countershaft 37 (see Figures 1, 27 and 31). The outboard end of this shaft is mounted on a bearing carrying plate 163 which is secured by a

bolt 164 in a suitable recess 165 provided in the rear standard 3. This standard has an oppositely positioned seat 166 to receive the bearing plate 163 when the countershaft is shifted to the opposite side of the machine (see Figures 16 and 17).

Having reference now to the front end of the machine and to Fig. 28 of the drawings it will be seen that the positions of the forming roll 22 and idler roll 27 may be reversed. The bearing block seats 24 and 29 of the standard 2 are designed to interchangeably receive the bearing carrying blocks 28 of the rolls 22 and 27 respectively. As the stock will be fed from the opposite side of the machine the stock guide F must be moved to the opposite side of the machine. Accordingly the end standard 2 is provided with identical oppositely positioned bolt receiving openings 167 for the reception of the bolts which secure the stock guide F in place.

The standard 2 is likewise provided with two sets of bolt openings 168 which are oppositely positioned so that the stock clamp and bender D and E may be shifted from one side to the other side of the machine.

Moving the stock guide F from the left to the right side of the machine will in no way interfere with the proper operation of this device as it is constructed so that stock can be fed equally well in either direction through it. By reference to Fig. 2 of the drawings it will be seen that at its inboard end this device is rounded as at 190 to overhang the idler roll 27 and rounded as at 191 to fit beneath the feed roll 7. The opposite end of the guide is similarly shaped and will properly fit between the feed roll 7 and the idler roll 27 when said last named roll is moved to the opposite side of the machine.

When the forming roller 22 and cutter assembly B are moved to the opposite side of the machine it is necessary to substitute a different cutter assembly which will be of similar construction and operation to that described and specifically illustrated in Fig. 20 of the drawings with the exception that the cutter fingers will incline in the opposite direction and the cutting edge of the fingers will be made to properly engage and sever the stock on the mandrel. The same spiral groove arrangement 136 will be provided for projecting and retracting the cutter fingers.

In making the change from a right to a left winding or coiling machine the connection between the cam C and the idler roller shaft 33 is moved to the opposite side of the machine. To make this possible the base 1 is provided at both sides of the machine with openings 169 (see Figure 27) for the reception of the bolts 53 which secure the standard 52 in position.

I claim:

1. An apparatus for coiling metal stock comprising, front, rear and intermediate standards, a power shaft journaled in the rear and intermediate standards, a stock feed roller shaft rotatably mounted in said front and rear standards, the front end of said stock feed shaft being journaled in a vertically movable support and carrying a feed roll, a mandrel rotating shaft rotatably mounted in the front and intermediate standards and being restrictedly vertically movable in the front standard, a mandrel detachably connected axially to said shaft, a forming roll shaft rotatably mounted in said front and intermediate standards and carrying a forming roll, an idler roll shaft rotatably mounted on said front standard and carrying an idler roll, all of said shafts with the exception of said idler roller shaft hav-

ing driving connection with said main power shaft, said stock feeding roll being above said mandrel and said forming and idler rolls being at opposite sides of said mandrel and in axial planes below the axial planes of said stock feeding roll and said mandrel, means associated with said forming roll for periodically severing said stock on said mandrel while the mandrel is being rotated and while the stock is being coiled thereabout, means for forcing the outer end of the feed roller shaft and the feed roller downwardly under a selected amount of pressure, and means adjustably positionable longitudinally of the mandrel and engaging the side of the stock thereon and causing the stock to be coiled in opened spirals of predetermined pitch.

2. A construction as defined in claim 1 wherein, the idler roll is adjustably movable longitudinally of the mandrel and constitutes the means which gives the stock a spiral winding of predetermined pitch, a rotatable cam having therein an endless cam face, drive means between said cam and the main power drive shaft, means operatively connecting the endless camway of said cam to said idler roll for moving said roll longitudinally of the mandrel, and said camway and said operative connection operating to project and retract said idler roll after a predetermined number of spiral convolutions of said stock have been wound about said mandrel.

3. A construction as defined in claim 1 wherein, and describing more specifically, that the means which is adjustably positionable longitudinally of the mandrel as comprising the idler roller and the same as having a marginal annular and peripheral formation which engages the side of the stock while it is being coiled on the mandrel and further comprising a connection with the shaft of the idler roller for periodically reciprocating said shaft to retract said idler roller from its coil opening position during the end winding formation of the coiled stock, holding said idler roller in its retracted position during the initial winding of a new coil of stock and returning said idler roller to its coil opening position during the open spiral winding of the new coil.

4. A construction as defined in claim 1 but describing more specifically that said front and intermediate standards are reversely arranged and provided to permit the mounting thereon of the forming roller and the idler roller and their carrying shafts in reversely interchanged positions, with the stock feeding roller and its carrying shaft in its one position, and said feeding roller and its direction of feeding rotation of the stock can be reversed by a reverse operation of the power shaft in its one position of mounting and operation.

5. A machine for coiling metal stock comprising, a driven rotatable circular mandrel, a driven stock feeding roll above said mandrel and engaging stock on said mandrel, a driven rotatable form roll at one side of said mandrel and engaging stock thereof, an idler roll at the opposite side of said mandrel and engaging the side of stock on said mandrel to cause said stock to be wound about said mandrel spirally and of a predetermined pitch, a cutter associated and rotatable with said forming roll, said cutter comprising a plate arranged in parallel spaced relationship to the outer side face of said forming roll, a cutter blade mounted in said space and provided with an extension element, said cutter plate provided with a spiral groove for the reception

of said cutter blade extension element, and said cutter plate being rotatably adjustable to project and retract said cutter blade, for the purpose described.

6. For use with a machine in which metal stock is coiled spirally about a mandrel, a stock feeding and aligning device comprising, a pair of opposed channeled plates, a guide block in each of said plates, said guide blocks having in their opposing faces opposed grooves forming a passageway for snugly receiving the stock, the outer of said plates being quickly detachable from the inner plate to provide for the insertion of stock into the passageway formed by said blocks, said plates being pivotally mounted for movement in a vertical plane, and said plates being further mounted to permit them to be adjustably rocked in a direction transverse the longitudinal axis of the plates.

7. In combination with a machine for coiling metal stock for the manufacture of coil springs and lock washers, means for initially bending the end of the stock into a semi-circle comprising a pair of rolls adapted to receive the stock between them, one of said rolls being rotatable on a fixed shaft, the other of said rolls being mounted to be swung concentrically about the fixed roll, means to swing said last named roll as described, and a clamp engaging said stock at a point in front of said rolls to prevent movement of said stock as the end thereof is bent about said fixed roll.

8. An apparatus for the purpose described, comprising, a positively driven rotating mandrel about which metal stock is adapted to be wound, a positively driven stock feeding roll above said mandrel and adapted to engage said stock, a positively driven forming roll at one side of said mandrel for engaging said stock and coiling it about said mandrel, an idler roll at the opposite side of said mandrel and having a beveled annular peripheral edge portion for engaging said stock laterally thereof and causing it to be spirally wound about said mandrel, said idler roll being adjustable longitudinally of its axis and of said mandrel to and from its coil pitching position whereby to vary the pitch of the spiral into which said stock is coiled, said roll being also movable longitudinally of its axis and of said mandrel retractedly from its adjusted coil pitching position, means automatically and periodically operated to move said idler roll out of its coil pitching position to flatly nest and eliminate pitch to the endmost convolution of the wound stock, and a stock cutter operating periodically for cutting said stock after a predetermined number of convolutions of the stock have been wound and end formed about said mandrel.

9. A construction as defined in claim 8 and describing more specifically that the automatically and periodically operated means for moving said idler roll out of its coil pitching position as comprising a positively driven rotatable cam having therein an endless camway and means connecting said camway and said idler roll for imparting retractive longitudinal movement to said idler roll during the end winding formation of the stock as wound on said mandrel.

10. A construction as defined in claim 8 wherein the positive drive for the mandrel includes a rotatable shaft provided with an internal bore, said mandrel extending into said bore and having therein a flattened end, a flat bar within said shaft bore and engaging the flattened end of the mandrel, and means carried by the shaft and engaging said bar for forcing the same un-

der pressure against the mandrel to clamp the same against rotative or longitudinal movement within the bore, whereby the mandrel is optionally clamped within the bore for rotation with the shaft or removable from the bore for replacement.

11. An apparatus for coiling metal stock comprising, a rotatable mandrel about which said stock is adapted to be coiled, a rotatable stock feeding roll for engaging said stock against said mandrel, a stock guide for delivering said stock in proper alignment to said feed roll, a rotatable stock forming roll at one side of said mandrel, a common power drive for said mandrel and said rolls, an idler roll at one side of said mandrel oppositely positioned in respect to said forming roll, said idler roll being adjustable longitudinally of its axis and longitudinally of said mandrel and being formed marginally, annularly, and peripherally, to engage the side of said stock, as it is coiled about said mandrel, whereby to open the convolutions of the coiled stock at a definitely predetermined pitch, rotatable means having driving connection with said main power means and acting to hold said idler roll in a definite coil pitching position during formation of the coiled stock and periodically retracting said roll from its coil pitching position whereby to flatly nest and eliminate pitch to the endmost convolution of the wound stock, and a cutter associated with said forming roll and rotatable therewith, said cutter acting to sever said stock after a predetermined number of convolutions thereof have been coiled about said mandrel.

12. A construction as defined in claim 11 wherein, a rotatable cam is provided and has drive connection with the main power drive, said cam being provided with an endless camway, a swing arm carrying therein a roller disposed in said camway, and an adjustable connection between said swing arm and said idler roll, whereby said idler roll is periodically retracted and projected a predetermined distance.

13. An apparatus for coiling metal stock comprising, a rotatable shaft carrying a mandrel, a rotatable shaft carrying a stock feeding roll, a rotatable shaft carrying a stock forming roll positioned at one side of said mandrel, a rotatable shaft carrying an idler roll at the opposite side of said mandrel, said idler roll adapted to engage the side of stock as it is coiled about said mandrel, said idler roll shaft being longitudinally movable, a cam provided with an endless camway, a connection between said endless camway and said idler roll shaft for periodically longitudinally reciprocating said shaft, a power shaft, a drive connection between said power shaft and said feed roll and said forming roll shafts, said drive connection including a counter shaft, a drive connection between the mandrel shaft and said power shaft, a drive connection between the mandrel shaft and said cam, standards for supporting all of said shafts, said shafts at their ends provided with blocks carrying shaft reception bearings, said standards provided with seats for interchangeably receiving the bearing blocks of the forming roll and idler roll, a pair of said standards provided at their opposite sides with seats for bearing carrying blocks for said counter shaft whereby said shaft may be positioned at either side of said standards, and the positions of the forming roll and idler roll and their shafts being interchangeable, for the purpose described.

14. A construction as defined in claim 13 wherein, a stock guide is provided for guiding the

15

stock to the feed roll and mandrel, said guide being mounted on one of said standards, said guide being constructed to permit stock to move therethrough in either direction, and said standard being provided with means for supporting said stock guide at either side of said mandrel.

15. A machine for coiling metal stock comprising a driven rotatable circular mandrel, a driven stock-feeding roll above said mandrel and engaging stock on said mandrel, a driven rotatable forming roll having a face thereof provided with at least one radial slot arranged at one side of said mandrel and engaging stock thereof, an idler roll at the opposite side of said mandrel and engaging the side of stock on said mandrel to cause said stock to be wound about said mandrel spirally and of a predetermined pitch, a

16

5 cutter associated and rotatable with said forming roll, said cutter including a rotatable plate having a face thereof provided with a spiral groove, the face of said plate being arranged with respect to the face of said forming roll so that the spiral groove in the face of said plate is 10 complementary to the radial slot in the face of said forming roll, at least one cutter blade provided with a lug mounted for reciprocal movement within said radial slot, the lug of said blade extending into and being in engagement with said spiral groove, and means for releasably locking said plate to said forming roll whereby rotation of said plate causes the projection and retraction of the cutter blade.

15 JOHN BALLA, SR.
